TAPPET MECHANISM

Gerald D. Line, Royal Oak, Mich., assignor to Eaton Manufacturing Company, Cleveland, Ohio, a corporation of Ohio

Application February 4, 1957, Serial No. 638,035

7 Claims. (Cl. 123—90)

This invention relates to tappet mechanisms and more particularly to novel one-piece spring means for use in combination with valve actuating tappet mechanisms for internal combustion engines.

Tappet mechanisms in the past involved the use of clip means as a restricting element, limiting outward movement of a piston member from the tappet body of the tappet mechanism. In conjunction with the limiting function, a resilient action was obtained from a separate spring means maintaining a push rod of the valve actuating mechanism in extended relation to the body of the tappet mechanism. The invention in this application pertains to the above structure and through the use of a simplified novel spring means provides for a compact one-piece unit insertable in tappet mechanisms effective to serve a dual function.

An object of this invention is to provide in a tappet mechanism comprising a tappet body and a piston or plunger member, a novel one-piece spiral spring means secured to the tappet body adapted to receive one end of a push rod for maintaining the push rod in extended relation from the tappet body.

Another object of this invention is to provide a tappet mechanism of the above sort wherein the spiral spring means limits the axial movement of the piston or plunger member.

A further object of this invention is to provide a tappet mechanism of the above nature wherein the spiral spring means, adaptable to receive the push rod, is capable by structural limitations of restricting or allowing relative rotative motion occurring between the tappet body and push rod during operation of the mechanism.

A still further object of this invention is to provide a dual purpose spiral spring means that is simple in structure and economical to produce having inherent characteristics of sustained operating life.

This invention can be further briefly summarized as containing novel and practical combinations and arrangements of parts hereinafter described and particularly set out in the claims hereof.

Further objects and advantages of the invention will appear from the following description taken in connection with the drawings forming a part of the specification and in which,

Figure 1 is a side view of the tappet actuating means and includes an enlarged cross-sectional view of the tappet mechanism containing the dual purpose spiral spring means.

Figure 2 is a top view of the dual purpose spiral spring means in its unassembled form.

Figure 3 is a fragmentary cross-sectional view of the push rod and tappet structure with a conical or spiral spring means modification.

Figure 4 is a top elevational view of the spiral spring means modification in its unassembled form.

Referring to the drawings for more specific details of the invention, a hydraulic tappet structure 10, shown more distinctly in Figure 1, comprises a cylindrical body

2

member 12, a base portion 14 formed as a part thereof, and an opening 16 formed by the body at the extreme end opposite the base portion.

5 Radially inwardly of the tappet body 12 is a piston member 18, axially movable within the tappet body and responsive to fluid pressure supplied to a high pressure chamber disposed between the piston and body wherein upon rotation of a cam member 20 a reciprocating motion is imparted to the tappet body and consequently, to the movable piston member through the medium of fluid trapped in the high pressure chamber.

10 The movable piston member is so constructed as to provide for a hollow fluid chamber 22, one end of which provides for a fluid passage 26 forming a valve seat 28. A circular disk-shaped valve member 30 is positioned axially between the base portion 14 and the fluid passage 26 and is resiliently held in intimate contact with the valve seat 28 by a spring member 32 interposed between the cage bottom 34 and the valve member 30. The piston member 18 is biased outwardly of tappet body 12 by a resilient spring 36.

15 At the opposite end of the fluid opening of the movable piston member is an end piece 38, formed of a certain cup-like curvature, having its convex side opposite the fluid opening 26 and the concave side facing the tappet body opening 16, the end piece 38 being so constructed as to provide a curved area adapted to receive the end portion 40 of a push rod 42. The push rod end is formed of a lesser diameter than a body portion 43 of the push rod 42 so as to provide a shoulder portion 44 for receiving a normally flat spiral spring means 46.

20 The spiral spring means 46 is formed to provide at its inner periphery an opening 48 for engageably receiving the shoulder portion 44 of the push rod 42. The outer periphery 50 is fixedly secured to the tappet body 12 allowing limited axial movement of the plunger or piston member 18, preventing the piston from an overly extended outward movement.

25 A rocker arm 52, pivotal in a slot 56 formed by a fixed member 54, is in constant engagement with one end of the push rod member 42. The push rod transmits the reciprocatory motion created by the cam member to the pivotal rocker arm which in turn actuates a valve member 58 in a like manner. Whereas, during a normal operation, the tappet mechanism serves to function to maintain zero or a predetermined small clearance in the valve gear train between the valve being actuated and the motivating cam, the spring function of means 46 serves to insure a maintenance of engagement between one end of push rod 42 and one arm of rocker arm 52.

30 In this manner should the tappet piston for any reason become bottomed in the tappet body the resilient action of means 46 is ever present to hold the push rod axially extended relative to the tappet body with one end engaging the push rod. It will be thus recognized that the push rod by reason of not being attached to the rocker arm is prevented from falling out of series related engagement therewith as part of the valve gear train and as a further relationship, the spring through the transmitted action of the push rod maintains the rocker arm in constant contact at its fulcrum point and at its valve stem contacting point, thus minimizing valve gear failure.

35 Figure 3 shows the aforementioned tappet mechanism and push rod member combined and connected with a normally conical spring means 60 from overextending outwardly from the tappet body. The conical spring means being of a resilient nature maintaining the piston 18 and the push rod 42 in a continuous contact position tending to eliminate clearance caused if piston sticking occurs. This particular figure demonstrates a possible modification of the dual purpose spiral spring means idea as used in valve actuating mechanisms.

From the foregoing description and accompanying drawings, it can be seen that the valve mechanism disclosed contains certain novel and practical features of simple and economical construction. Summarily, the tappet mechanism contains a one-piece spiral spring means which acts as a limiting means for the movable piston member and also as a resilient means maintaining the push rod in a constantly extended position in relation to the tappet body.

Furthermore, it will be seen that the spiral spring means is of a practical design nature and the ease of its assemblage into the tappet mechanisms facilitates large-scale production.

While the invention has been described in connection with certain specific embodiments, the mechanism involved is susceptible of numerous other applications that will readily occur to men skilled in the art. Therefore, the invention is limited only as indicated by the scope of the appended claims.

What I claim is:

1. A valve actuating mechanism including a pivotal rocker arm; a push rod engageable with one end of said rocker arm; a rotating member imparting reciprocal motion to a tappet mechanism, said tappet mechanism being axially spaced between and in intimate contact with said rotating means and said push rod, said tappet including a body member; a movable piston member therein, and a one-piece spiral spring means fixedly secured to said tappet body, said spring means having its inner periphery of suitable diameter adapted to engage one end of said push rod and so arranged on the tappet body as to maintain said piston from overextending outwardly from said tappet body while simultaneously biasing the push rod axially away from the body member.

2. A valve actuating mechanism including a pivotal rocker arm, a push rod engageable with one end of said rocker arm, a rotating means imparting reciprocal motion to a tappet mechanism, said tappet mechanism being axially spaced between and in intimate contact with said rotating means and said push rod, said tappet including a body member, a movable piston member therein and a one-piece spiral spring means fixedly secured to said tappet body maintaining said piston from overextending outwardly from said tappet body, said spring means having its inner periphery of suitable diameter adapted to receive one end of said push rod, and providing a resilient action for maintaining said push rod in continuous contact with said rocker arm.

3. A valve actuating mechanism including a pivotal rocker arm; a push rod engageable with one end of said rocker arm; a rotating means imparting reciprocal motion to a tappet mechanism, said tappet mechanism being axially spaced between and in intimate contact with said rotating means and said push rod, said tappet including a body member, a movable piston member therein, and a one-piece spiral spring means fixedly secured to said

tappet body allowing limited axial movement of said piston member outwardly of the body, said spring means having its inner periphery of suitable diameter to engageably receive one end of said push rod and maintaining said push rod in extended relation from said tappet body.

4. A valve actuating mechanism including a pivotal rocker arm, a push rod engageable with one end of said rocker arm, a rotating member imparting reciprocal motion to a tappet mechanism, said tappet mechanism being axially spaced between and in intimate contact with said rotating means and said push rod, said tappet including a body member, a movable piston member therein, and a one-piece spiral spring means fixedly secured to said tappet body, said spring means having its inner periphery of suitable diameter adapted to engageably receive one end of said push rod, said inner periphery so adapted as to frictionally maintain said push rod and said tappet in non-rotatable relationship to one another and to bias the push rod axially away from the body.

5. A valve actuating mechanism including a pivotal rocker arm, a push rod engageable with one end of said rocker arm, a rotating member imparting reciprocal motion to a tappet mechanism, said tappet mechanism being axially spaced between and in intimate contact with said rotating means and said push rod, said tappet including a body member, a movable piston member therein, and a one-piece spiral spring means fixedly secured to said tappet body, said means having its inner periphery of suitable diameter for engageably receiving one end of said push rod with said inner periphery so adapted as to provide relative rotatable motion between said push rod and tappet mechanisms.

6. A valve actuating mechanism including a tappet body, a movable piston member therein and a conical spiral spring means fixedly secured to said tappet body, said spring means adaptable to receive one end of a push rod maintaining same in extended relation from said tappet body, said piston member axially movable within said tappet body being limited from excessive outward motion by said conical spring means.

7. A valve actuating mechanism including a tappet body, a member axially movable in said body, a push rod having one extremity engageable with said member, a spring means disposed between said body and said push rod biasing said push rod axially away from said body and limiting axial outward movement of said member relative to said body, said spring means being of a spiral configuration with its largest diameter portion secured to said tappet body and its smallest diameter portion in engagement with said push rod.
